ELECTROLYTIC DEVICE

Preston Robinson and Carleton Shugg, North Adams, Mass., assignors to Sprague Specialties Co., North Adams, Mass., a corporation of Massachusetts

Application September 27, 1932, Serial No. 635,097

9 Claims. (Cl. 175—315)

The present invention relates to electrolytic condensers especially to those having a highly viscous or pasty electrolyte, and generally referred to as "dry" electrolytic condensers.

5 Dry electrolytic condensers comprise as a rule two metal foil electrodes of which at least one is of film-forming material, for instance of aluminum, tantalum, etc., while the other may be also of film-forming metal but may consist 10 of other material. One or both electrodes are provided with an electrolytically formed oxide film and are wound together into a roll with the interposition of a spacer which carries a more or less viscous electrolyte. The electrolyte as a 15 rule comprises a weak acid and preferably also the salt of a weak acid, for instance boric acid and ammonium borate, and a proper ionizing agent which as a rule comprises water and a viscous fluid, for instance a polyhydric alcohol, as 20 glycerine or ethylene glycol. The electrolyte may also comprise one or more inert substances to increase its viscosity.

To maintain the proper operating characteristics of such condensers it is essential to maintain 25 their original moisture content and to prevent access of moisture from the outside, as well as evaporation of the water from the electrolyte. For this reason as well as for mechanical protection and prevention of access of outside 30 contamination, it has been found advisable to seal such condensers in containers. Various containers have been proposed for this purpose: for instance, rigid metal containers which sealingly enclose the condenser, or cardboard containers 35 preferably impregnated with a wax, for instance, paraffin. In both types of containers as a rule special provisions are taken to keep liquid and air tight those portions of the device where the electrodes, for the purpose of forming the outside 40 terminals or to be connected to outside terminals, project from the container. For instance, in metal containers the projecting portions of the electrodes are surrounded by gaskets, whereas in case of cardboard containers, as a rule a sealing 45 compound is provided which surrounds the projecting portions of the electrodes.

While as stated the containers should provide 50 for a substantially air and moisture-proof enclosure of the condenser, there should be at the same time provided an escape for the gases, which gases develop during the operation of the condenser as the passage of current through the condenser liberates oxygen and hydrogen at the electrodes. If these gases are not afforded an 55 escape, they build up to considerable pressures

and may cause the condenser to blow up. Also, such gases form an explosive mixture which might be ignited by a spark occurring in the condenser during its operation, unless the gases were allowed to escape.

Both of the above containers have obvious drawbacks. The rigid metal containers themselves and the sealing and venting means used in conjunction therewith are expensive and represent a large portion of the manufacturing cost 10 of the condenser unit.

While cardboard containers are less expensive, they have the drawback of insufficient mechanical protection, and when the container is damaged, which is quite likely to occur, especially 15 when the condenser is mounted by means of clamps, the air tightness of the container is destroyed. Nor do such containers afford sufficient mechanical protection against denting or of otherwise damaging the condenser during its 20 handling and mounting.

The present invention has for its purpose to overcome the disadvantages of high cost of the metal container and the insufficiency in regard to mechanical protection of the cardboard container and to provide a novel construction of a 25 protecting envelope which is simple and cheap, mechanically strong, not subjected to be damaged and protecting the condenser from being damaged and which permits the provision of simple 30 means for the air and liquid tight sealing of the condenser, and for the escape of gases developed in operation.

Our novel construction has also further advantages later to be pointed out.

Our invention also relates to a process for the assembly of condensers in our novel type of envelope and to novel constructional features to be pointed out.

The invention will be more fully explained with 40 reference to the drawing forming part of this specification, and in which:

Figure 1 is a side elevation partly in section showing a condenser embodying our invention.

Fig. 2 is a perspective view, partly broken away, 45 of a preferred form of metal envelope used in our invention.

Fig. 3 is a side view partly in section showing a condenser in the process of assembly while subjected to compression after being placed in the 50 metal envelope.

Fig. 4 is a top view showing the condenser in the compression clamps after its compression.

Fig. 5 is a top view of the condenser after it has been removed from the clamps, and the ridges 55

formed by the excess material of the envelope are folded over.

Fig. 6 is a fractional side view showing the electrode terminal connections with a cross support for same.

Referring to Fig. 1, there is shown an electrolytic condenser for instance a condenser to be used in the filter circuits of radio receiving sets and which comprises two aluminum foil electrodes 1 and 2, one of which, for instance electrode 1, is provided with an electrolytically formed film.

Interposed between the two electrodes 1 and 2 is a gauze spacer 3 carrying an electrolyte. The electrolyte comprises, for instance, a solution of ammonium borate and boric acid, and water and glycerine as ionizing agent, and if desired also an inert substance, the electrolyte having a low fluidity, for instance, pasty consistency.

The aluminum foils 1 and 2 have integrally projecting portions 4-4 to which are riveted by means of rivets 5-5 suitable terminals 6-6 respectively. There is preferably also provided a cross supporting member 7 of insulating material interconnecting the two projections 4-4, which member is riveted to said projections preferably by means of the aforesaid rivets 5-5. Such a cross support considerably stiffens the two terminals and provides for their proper spacing.

The envelope 8 consists of a thin metallic sleeve closed at one end, and is preferably a seamless tube having thin metal walls, for instance, an aluminum tube having a wall thickness of the order of .01" to .015". Other metals such as tin can also be used, however aluminum because of its all-round mechanical properties and especially greater strength, is especially suited. To get satisfactory results it is essential that the metal envelope should be collapsible with the exertion of comparatively small pressure, and on the other hand should be sufficiently resistant to mechanical damaging so as to afford sufficient protection for the condenser.

The condenser proper, which is assembled in the form of a roll—as a rule of cylindrical cross-section—is placed within the envelope 8, which has a cross-section slightly exceeding that of the condenser, so that the condenser fits easily therein, but without substantial interspace, and which envelope extends at its open end 19 beyond the condenser.

The envelope with the condenser disposed therein is then placed in a fixture (see Figs. 3 and 4) which consists, for instance, of four complementary movable jaws 20, 21, 22 and 23 which, when the jaws are closed, outline the shape to be imparted to the condenser. For instance, in the illustration the contour of the compressed condenser is of substantially oblong shape with the short sides rounded. The fixture is also provided with a bottom plate 15, which may be also in the form of a movable jaw member instead of the fixed plate as shown in the drawing.

The jaws are gradually approached to each other simultaneously or in the present case by first closing jaws 20 and 21 and thereby press the envelope together with the condenser to conform to the shape of the cavities. Thereby the envelope surrounds the condenser so that all air space between the condenser and the envelope and also within the condenser is eliminated. It should be noted that the compression slightly reduces the contour area of the envelope and the excess material of the envelope is drawn into ridges 12 which are illustrated in the drawing in somewhat exaggerated manner.

After the condenser is compressed, but while still in the fixture, a fluid sealing compound 11 which hardens in situ is poured by means of a jet as indicated in Fig. 3 (or in any other suitable way) to fill out the extending portion 19 of the envelope and thus cover the condenser.

The compression of the condenser, as has been stated, forces the air out from between the condenser and the envelope and also from the condenser, and as the sealing compound is poured in and hardens while the condenser is held compressed, formation of new air pockets within the condenser or between the condenser and the envelope is prevented. The prevention of air pockets is of great importance for the maintenance of the proper operating characteristics of the condenser, as ionization of the air and secondary chemical reaction due to the presence of air, may otherwise deleteriously influence the properties of the condenser.

The escape for the gases which develop during operation of the condenser, is provided by using such sealing compounds, for instance certain types of pitch, which are sufficiently porous to permit the passage of the developed gases, which, however, are not sufficiently porous to permit escape of the water vapor from the condenser (except for minute amounts carried out by the gases), or to admit to the condenser moisture or impurities from the outside. It should be also noted that this construction also prevents the formation of gas pockets by the gas liberated during operation. The intimate contact of the metallic envelope with the condenser also provides for excellent heat transfer from the condenser to the outside.

The ridges 12-12 can be flattened out as indicated in Fig. 5.

Instead of using a four-part jaw, other jaw constructions may be conveniently used.

As will appear, our invention provides for a simple and cheap construction which affords good mechanical protection of the condenser, insures an air and liquid-tight sealing therefor and permits the escape of gas, which construction eliminates and prevents formation of air and gas pockets within the condenser and between the condenser and envelope, and provides for a good heat transfer from the condenser to the outside.

While we have described our invention with reference to a specific construction, we do not wish to be limited to such construction, but desire the appended claims to be construed as broadly as permissible in view of the prior art.

In the claims the term "dry condenser" refers to a condenser having a viscous or pasty electrolyte.

What we claim as new and desire to secure by Letters Patent is:

1. In an electrolytic condenser in combination a condenser body comprising two metal foil electrodes and a highly viscous electrolyte interposed between said electrodes, and a protecting envelope comprising a thin-walled metal tube having at least one axially-extending fold, said tube tightly cinching and directly contacting with said body over its entire circumferential area and being closed at one end and projecting beyond the body at its open end, and a sealing compound filling out the space formed by the projecting end of the envelope above the body.

2. An electrolytic condenser comprising in combination a condenser body having two metal foil electrodes and a highly viscous electrolyte interposed between said electrodes, said electrodes

- having integral projecting portions for their connection to outside terminals, and a stiffening and spacing member of insulating material connected to said projecting portions and a thin-walled metal tube snugly surrounding said body and in intimate contact therewith over its whole circumferential area, said tube having at least one axially-extending fold and being closed at one end and extending beyond the body at its open end, 5 said extending end surrounding said projecting electrode, and a sealing compound which hardens in situ filling out said extending portion of the tube, said electrode portions and stiffening means being fixed in position solely by the hardened compound.
- 10 3. An electrolytic condenser comprising a condenser body of the dry type and a protecting envelope, consisting of an easily collapsible thin-walled metal tube which is open at one end and closed at the other end, said envelope having at least one fold parallel to its axis and girthing said condenser body.
- 15 4. An electrolytic condenser comprising a condenser roll of the dry type, a protecting envelope consisting of a collapsible metal tube of approximately .01 inch thickness, which surrounds and intimately girths said condenser roll around its whole circumferential area, said envelope being provided with at least one axially-extending ridge to tension same about the roll.
- 20 5. An electrolytic condenser comprising a condenser roll of the dry type, and a protecting envelope consisting of a thin-walled aluminum tube having at least one axially-extending fold and being open at one end and closed at the other end, said metal tube tightly girthing said condenser roll.
- 25 6. An electrolytic condenser comprising a con-
- denser body of the dry type, and a protecting envelope consisting of an easily collapsible thin-walled metal tube having at least one axially-extending fold, said tube being open at one end and closed at the other end, and snugly surrounding and tightly girths the condenser body, and a sealing compound to seal the open end of the envelope.
- 30 7. An electrolytic condenser comprising a condenser roll of the dry type, and a protecting envelope consisting of an easily collapsible thin-walled metal tube cinching said condenser roll and having at least one integral ridge parallel to its axis and formed by the excess material of the envelope when drawn to cinch said condenser roll.
- 35 8. An electrolytic condenser comprising a condenser roll of the dry type, and a protecting envelope consisting of a collapsible metal sleeve and contacting the side of the roll with a cornerless surface, said envelope having integral axial ridges causing said envelope to press against said roll and to intimately contact therewith around its entire surface area.
- 40 9. In the process of manufacturing dry electrolytic condensers, the steps which comprise, assembling into a roll two electrode foils with the interposition of a highly viscous electrolyte, surrounding said roll with a collapsible metal sleeve which fits around said roll and projects beyond at least one end thereof, deforming said sleeve to reduce its cross-sectional perimeter and to uniformly cinch said roll over its entire cylindrical surface, and pouring a sealing compound which hardens in situ into the open end of the sleeve while the condenser is thus compressed.
